UNITED STATES PATENT OFFICE.

SIMON NEWCOMB, OF BIDDEFORD, MAINE.

BOOT AND SHOE.

SPECIFICATION forming part of Letters Patent No. 237,581, dated February 8, 1881.

Application filed November 20, 1880. (Model.)

To all whom it may concern:

Be it known that I, SIMON NEWCOMB, of Biddeford, in the county of York and State of Maine, have invented a new and useful Improvement in Boots and Shoes, which improvement is fully set forth and described in the accompanying specification and drawing.

The object of my invention is to prevent the strain on the buttons of button-boots from tearing the leather and the pulling out of the buttons.

It consists of two stays or braces, of cloth or other suitable material—one, A, stitched at the back seam of the upper, and the other, B, stitched at the vamp, and both extending nearly to the front seam, substantially as shown in the drawing, but not fastened there. The buttons are sewed or otherwise fastened through the outers, stays, and linings. In use, the strain on the buttons being sustained by the stays, the leather does not tear from the seam and the buttons do not pull out.

The accompanying drawing shows the button side of the upper part of the boot without the lining, X being the outer leather; A, the stay from the back seam; B, the stay from the vamp. The dotted lines *a a* and *b b* represent the stitching at the back seam and the vamp, respectively, and *o o* represent the fastening of the buttons.

In shoes only the stay from the vamp is necessary.

This invention is applicable to boots or shoes of any material.

What I claim as new, and desire to secure by Letters Patent, is—

As an improvement in boots and shoes, the combination of the stays A and B with the vamp and quarters, all attached and arranged substantially as shown and described.

SIMON NEWCOMB.
